LIGHTING FIXTURE

John F. Livers, Decatur, Ill., assignor to Farles Manufacturing Company, Decatur, Ill., a corporation of Illinois

Application August 15, 1940, Serial No. 352,732

1 Claim. (Cl. 240—78)

My invention relates to that class of lighting fixtures which employ the recently developed fluorescent tubes as their light source.

The general acceptance by the public of this type of lighting has resulted in the production of fixtures to employ such a light source, in which, no doubt due to the haste in which they were designed, there is present an amount of glare which is considerably above the standard requirements.

It is now recognized that fixtures possessing glare above the minimum have a deleterious effect upon the eyesight of the user, which results in undue fatigue, etc.

My invention has for its principal object to produce a fluorescent lighting fixture, which will reduce the glare below the minimum requirements of the I. E. S. without sacrifice of efficiency.

A further object is to construct such a fixture so that almost all of the output of the light source shall be available for useful illumination.

A further object is to so construct the fixture that it will (although attaining a high degree of efficiency) have easy accessibility, and produce a pleasing quality of light.

A further object is to permit the majority of the lumens, emitted by the source, to pass to the working plane without producing glare and to reflect and redirect a majority of the remaining lumens downwardly.

A further object is to utilize the remaining lumens to illuminate the walls and ceiling.

My means of accomplishing the foregoing objects may be more readily understood by reference to the accompanying drawing which is hereunto annexed and forms a part of this specification in which:

Fig. 1 is a cross sectional view of my device;

Fig. 2 is a bottom plan view. Similar reference numerals refer to similar parts throughout the entire specification.

As shown in the drawing my fixture comprises a frame 11, which carries a pair of curvilinear reflectors 10 and 12, which are mounted above and parallel to the fluorescent light source 14, which is mounted in the frame 11. These reflectors 10 and 12 are preferably designed to receive and redirect by reflection the lumens emitted from approximately 125 degrees of the circumference of the light source 14.

Extending longitudinally of the fluorescent tubes 14, I mount reflectors 16 and 17. They may be secured to the frame 11, in any suitable or desired manner. These longitudinal reflectors 16 and 17 are angular in cross section and have

their surfaces 18 and 20 coated with a reflecting medium. In practice I have found it preferable to mount these longitudinal angular reflectors 16 and 17, with the apex of the angle in the plane of the axis of the fluorescent tubes 14. Obviously this may be varied according to the amount of light flux it is desired to reflect into the upper or lower hemisphere.

Below the plane of the light source 14, and parallel thereto, I mount a plurality of shields or screens 22. These screens are preferably coated with a mat reflecting surface, having a low absorption quality. If desired they may be made adjustable. I have found in practice that in the majority of cases, it is not necessary. It suffices if they shield the light source 14, from the eyes of an observer except at a point directly below the fixture.

In practice it has been found that this construction allows all of the lumens emitted from 155 degrees of the circumference of the light source 14, to pass downwardly to the working plane.

The remainder of the light rays, not reflected or passing downwardly as described, will pass without obstruction or reflection to the walls, lighting them with a softly diffused light entirely free from glare.

It will be apparent to persons skilled in the art that by varying the curvature of the reflectors 10 and 12, with relation to the position of the light source 14, it will be possible to distribute, in any desired direction, that portion of the light flux which is controlled by these reflectors.

Referring to Fig. 1 it will be seen that the reflector 12 is so shaped that its lower edge projects perpendicular for the distance of the diameter of the fluorescent lamps then outwardly in a gradual arc until a point directly above the apex of one of said angular reflectors, then continuing parallel to the working plane in a horizontal direction beyond the said angular reflector. While reflector 10 is so shaped that its lower edge projects perpendicular for the distance of the diameter of the fluorescent lamps then outwardly in a gradual arc until it reaches a point directly above the apex of one of said angular reflectors where it curves sharply and downwardly to a point beyond said angular reflector. This construction provides a novel means of intensifying a portion of the lumens directly on the working plane by gathering and redirecting the rays as in reflector 10 while at the same time providing adequate illumination as in reflector 12.

Preferably the ends 24 and sides 26, of the fixture are opaque. If it is desired to avoid the contrast caused thereby, they can be formed of translucent glass or of a translucent plastic.

Although I have described a specific shape for the fixture, such description is solely to supply an illustration of the preferred embodiment of the invention, and I do not desire to be understood as being limited to such specific shape or construction, except as such limitations may appear in the hereinafter contained claim.

Having described my invention, what I regard as new and desire to secure by Letters Patent is:

In a fluorescent lighting fixture, a frame having side and end walls, a pair of fluorescent lamps having their ends mounted on the end walls of said frame and in spaced parallel relationship, their axes being in the same horizontal plane, a pair of reflectors angular in cross section mounted on the inside of a side wall, each of which comprises two flat surfaces meeting at an apex in the plane of the axis of the adjacent lamp, said reflectors extending longitudinally of and parallel to said lamps, a plurality of parallel

shields mounted below said lamps which shield the eye of an observer but permit direct and reflected rays to reach the working plane, and a pair of curved reflectors one for each lamp mounted above said lamps to redirect the direct and part of the reflected rays outwardly and downwardly, one of said curved reflectors being shaped so that its lower edge projects perpendicular for the distance of the diameter of the fluorescent lamps, then outwardly in a gradual arc until a point directly above the apex of one of said angular reflectors, then curving sharply downwardly to a point beyond said angular reflector, the other of said curved reflectors being shaped so that its lower edge projects perpendicular for the distance of the diameter of the fluorescent lamp, then outwardly in a gradual arc until a point directly above the apex of the other of said angular reflectors, then continuing parallel to the working plane in a horizontal direction beyond the said angular reflector, whereby varying intensity of illumination falls on the working plane.

JOHN F. LIVERS.
